Patented Oct. 23, 1928.

UNITED STATES PATENT OFFICE.

BENJAMIN F. GILLES, OF WATERTOWN, WISCONSIN, ASSIGNOR TO G. B. LEWIS COMPANY, OF WATERTOWN, WISCONSIN, A CORPORATION OF WISCONSIN.

CLINCHING TOOL.

Application filed August 6, 1926. Serial No. 127,613.

This invention relates to certain new and useful improvements in clinching tools and refers more particularly to a device for clinching nails and the like used in the manufacture of boxes and other containers.

Heretofore nails have been merely bent or struck over to obtain the desired clinching effect, but this method has many objections, one of which is that a nail point thus turned or struck over in a short time will work itself to a position with its point slightly raised. This, of course, is extremely objectionable, as the point of the nail thus exposed continually catches one's clothing and oftentimes causes serious cuts to the person handling a container so nailed.

With the above and other objections in mind this invention has as an object the provision of means by which a nail point is directed back into the work.

Another object of this invention resides in the provision of a tool which is relatively light, which accomplishes its object in a highly satisfactory manner and which is extremely simple in design.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a perspective view of a clinching tool embodying my invention;

Figure 2 is a bottom view of the working end thereof, and

Figure 3 is an end view of my improved tool showing the manner of application.

Referring now more particularly to the accompanying drawing in which like numerals designate like parts throughout the several views, the numeral 5 designates any piece of work, such as a box or other container top to which it is desired to secure a cleat or other means 6 by nails 7. It is desirable that the nails 7 be long enough to

penetrate the work or cover 5 and the cleat 6 with a portion thereof extending therethrough to be turned over so that it forms a positive tie between the two pieces, and to this end I have designed the clinching tool, 60 now about to be described.

The tool proper consists of a body member 8 preferably of round stock, although any other cross-sectional shape will be satisfactory, with one end 9 thereof slightly 65 bent at an angle to the main portion. The bottom of the member at its end 9 is flattened, as at 10, to provide a work engaging face and has a slot 11 therein arranged at right angles to the face 10 to form forks 12. 70 The opposite end of the body portion has a rod 13 passed therethrough to form a handle for convenience in manipulating.

To apply my improved tool, it is placed with the face 10 flat on the work and the nail 75 engaged in the slot 11, see Figure 3. While held in this position, the end or point of the nail is struck over one fork 12, directing the point of the nail back into the work as shown in dotted lines in Figure 3. The tool is then 80 removed and the looped or bent over nail end is driven into the work, as will be readily evident.

It will be noted that the flattening of the end 9 is such that the forks 12 are longitudinally tapered thus providing means for forming a small or large loop on the extended nail end, depending upon the length of extension of the nail.

What I claim as my invention is:

1. A tool of the character described, comprising a body portion having one end flattened and directed at an angle to the body portion to provide a work engaging face and having a slot therein to receive a nail extension, and means over which the nail may be struck to shape the nail extension into substantially a loop and direct the point thereof back on itself.

2. A tool of the character described, comprising a body portion having a slot therein adapted to embrace a nail extension, and means over which the nail may be struck to direct its point back upon itself, said means being tapered to accommodate nail extensions of different lengths.

3. A tool of the character described, comprising a body member having a slot therein to receive a nail extension, said slotted portion of the body member having its under

surface substantially flat and its upper surface arcuate, and prongs defined by the slot in the body member and providing means over which the nail extension may be struck to direct its point back upon itself and permit the same to be clinched.

4. A tool of the character described, comprising a body member having one end por-

tion bent at an angle thereto, said end portion being longitudinally slotted and having its bottom surface substantially flat and its top surface arcuate, and the prongs formed by the slotting of said end portion providing means over which a nail may be clinched. 10

In testimony whereof I affix my signature.

BENJAMIN F. GILLES.
